FIG. 1

FIG. 2

FIG. 3

To all whom it may concern:

Be it known, that we, Daniel D. Whyte and Jerome J. Stern, both citizens of the United States, respectively, residing at Brooklyn, New York, and Englewood, New Jersey, have invented a new, original, and ornamental Design for a Flexible Cover for Spherical Articles, of which the following is a specification, reference being had to the accompanying drawing, forming a part hereof, in which

Fig. 1 is a plan view of a flexible cover for spherical articles, showing our new design.

Fig. 2 is a front elevational view thereof.

Fig. 3 is an end elevational view thereof.

The rear view of the cover is the same as the front view.

We claim:

The ornamental design for a flexible cover for spherical articles, as shown and described.
